INVENTOR

Frederick C. Andressen,
By Frederick V. Winters,
Attorney

UNITED STATES PATENT OFFICE.

FREDERICK C. ANDRESEN, OF BROOKLYN, NEW YORK.

HAIR-CURLING DEVICE

1,335,313.

Specification of Letters Patent. Patented Mar. 30, 1920.

Application filed November 3, 1919. Serial No. 335,340.

To all whom it may concern:

Be it known that I, FREDERICK C. ANDRESEN, a citizen of Germany, residing at Brooklyn, in the county of Kings and State 5 of New York, have invented certain new and useful Improvements in Hair-Curling Devices, of which the following is a full, clear, and exact specification.

This invention relates to hair curling devices, and has for its object to provide a hair curler of the clamping jaw type which may be more conveniently handled than such devices as heretofore made.

It is the aim of this invention to provide 15 a separate and distinct curl-holding member to which the clamping jaws are pivoted or hinged and from which said jaws may be swung back so as to in no way interfere with the wrapping of the hair upon or about said 20 intermediate curl-holding member. Other objects will appear as the description proceeds.

The invention will be first hereinafter described in connection with the accompanying 25 drawings, which constitute part of this specification, and then more specifically defined in the claims at the end of the description.

In the accompanying drawings, wherein 30 similar reference characters are used to designate corresponding parts throughout the several views:—

Figure 1 is a plan view of one embodiment 35 of the invention, showing the clamping jaws closed upon the curl-holding member.

Fig. 2 is a perspective view of said device 40 with the clamping jaws swung back away from the curl-holding member, as when the hair is to be wound about said member.

Fig. 3 is a perspective view of the device 45 showing how it is held in the hand when latching or unlatching the clamping jaws, the hand being indicated in broken lines.

Fig. 4 is a plan view of a modified form 50 of the device.

Fig. 5 is a side elevation of the same in closed position, and

Fig. 6 is a perspective view of said modified form of the invention in open position.

Referring first to Figs. 1, 2 and 3 of the drawings, 1 designates the curl-holding member which in this instance comprises a wire loop to one end of which there are secured diverging transverse pieces 2 and 3 as by solder 4. To each of said transverse

pieces 2 and 3 is hinged a clamping jaw adapted to swing into either of the positions shown in Figs. 1 and 2. Said clamping jaws are designated 5 and 6, respectively 60 and are shown as made of solid strips of resilient or spring metal. When closed or folded upon the hair-holding member 1, said jaws 5 and 6 extend slightly beyond the free end of said member. For holding the jaws 65 in this closed position a latching loop 7 is hinged to the free end of one jaw, and the free end of the other jaw is bent slightly outward so as to retain the loop in engagement therewith, as will be readily understood from Figs. 1 and 3. The solid jaws are also preferably made narrower than the hair-holding loop 1 so that the curl of hair 8, when wound upon said loop as shown in Fig. 3, will be pressed directly between the 75 jaws.

When the hair is to be wound upon the member 1, the jaws 5 and 6 are swung back to the position shown in Fig. 2 where they are entirely out of the way and do not interfere in any way with the winding of the hair about said member. After the hair is in place on the holding member 1, the jaws are swung to closed position, Fig. 3, and the free ends thereof pressed together between 80 the thumb and finger while the latching loop 7 is slipped over the bent end 9 of the upper jaw. The tension in the jaws, which are bowed over the hair, will hold the latch in position. 85

Referring now to Figs. 4, 5 and 6, in this modified form of the invention the hair-holding member 10 is made of a solid strip of metal while the clamping jaws 11 and 12 are made of looped wire of slightly greater 90 length and width than said member 10. The jaw loops are hinged to one end of the member 10 at 13, and the free ends of said jaws are adapted to be fastened together by a latch 14 hinged to one jaw and having a 100 hook 15 to engage the end of the other jaw, there being a bent finger piece on the free end of the latch, as at 16, for raising it from its closed position, Figs. 4 and 5, in which it rests on the upper surface of the hair holding member. The modified form of the device is used in the same way as illustrated in Fig. 3. 105

Having thus described my invention, what I claim as new and desire to secure by 110 Letters Patent of the United States is:—

1. In a hair curling device, the combina-

tion with a curl-holding member having rigid transverse pieces extending above and below the same at one end, of clamping jaws hinged respectively to said transverse pieces and adapted to embrace said member.

5. 2. In a hair curling device, the combination with a curl holding member, of clamping jaws hinged to one end of said member and adapted to swing toward and away
10 from opposite sides thereof, and an angu-

larly bent latch hinged to the free end of one jaw and adapted to extend across the end of the curl holding member and engage the free end of the other jaw for retaining said jaws in position to embrace said member on opposite sides. 15

In testimony whereof I have signed my name to this specification.

FREDERICK C. ANDRESEN.
